United States Patent Office.

WILLIAM W. LYMAN, OF WEST MERIDEN, CONNECTICUT.

Letters Patent No. 105,583, dated July 19, 1870.

IMPROVEMENT IN CAN-OPENERS.

The Schedule referred to in these Letters Patent and making part of the same.

To all whom it may concern:

Be it known that I, WILLIAM W. LYMAN, of West Meriden, in the county of New Haven and State of Connecticut, have invented a new Improvement in Can-Opener; and I do hereby declare the following, when taken in connection with the accompanying drawing and the letters of reference marked thereon, to be a full, clear, and exact description of the same, and which said drawing constitutes part of this specification, and represents in—

Figure 1, a side view, and in

Figure 2, a view from the under side, looking up.

This invention relates to an improvement in can-openers, the object being to make the opener adjustable to different sized cans; and

The invention consists in combining with a fixed rotary cutter an adjustable pivot, constructed so as to be inserted through and turn under the cover.

A is the arm or handle, in which a revolving cutter, *a*, is arranged, projections being formed upon the handle to support the cutter, and the inside part, *d*, of the projection forms a guide to govern the depth or run of the cutter.

B is the pivot, the lower end of which is turned at an angle, and formed into a point at *b*.

The said pivot B is formed on an arm, D, and set onto the principal arm A, and the two secured together by a set-screw, E, and one or the other, or both, of the arms slotted, so that they may be extended, as denoted in broken lines, fig. 1, thus adjusting the radius of the circle described by the cutter *a*, with the pivot B as its center.

The point *b* is inserted through the metal and turned down until the pivot B passes through and the cutter and pivot stand in the relative position to the cover or surface to be cut, as denoted by broken line, fig. 1.

I claim—

The combination of the revolving cutter *a* and the pivot B, constructed with the point *b*, and formed upon an arm, D, and the set-screw E, so that the said pivot and cutter are made adjustable to each other, substantially as described.

Witnesses: WILLIAM W. LYMAN.
